CLAIM

The ornamental design for an interactive quiz machine, as shown and described.

DESCRIPTION

FIG. 1 is a top, front, and left side perspective view of our new design for an interactive quiz machine;

FIG. 2 is a front view thereof;

FIG. 3 is a left side view thereof;

FIG. 4 is a top view thereof;

FIG. 5 is a rear view thereof; and,

FIG. 6 is a bottom view thereof.

The broken lines are for illustrative purpose only and form no part of the claimed design.
